PRESSING MACHINE OPERATING DEVICE

Samuel E. Osborn, Catonsville, Md.

Application December 28, 1945, Serial No. 637,526

2 Claims. (Cl. 38—41)

1

This invention relates to laundry machines and more particularly to operating devices for steam pressing machines capable of pressing garments and dampening same with steam and at the same time to do effective work in creasing and flattening the clothing, in a permanent manner.

In a particular form of pressing machine used, the head and buck press the clothing, garments or fabrics between them, using valves for introducing fluid motive power into a cylinder with a piston to actuate the mechanism provided for the purpose, to bring the head down under pressure on the buck, the steam being introduced incidently by the manual operation of a valve controlling the steam line to the head. The operation of this form is dependent on the physical efforts of the user and his personal judgment. The use of the machine therefore becomes difficult, requires continual alertness and is tiresome, all of which reduces its field of utility and increases costs in producing results from it.

The object of this invention is to provide a new and improved pressing machine that will avoid one or more of the disadvantages and limitations of the prior art.

An additional object of the present invention is to provide a new and improved pressing machine that can be operated through the use of fluid motive power to give an intermittent pressing action while at the same introducing the steam desirable for dampening the material being pressed.

A further object of the invention is to provide a new and improved pressing machine that will operate effectively and expeditiously under fluid motive power, requiring but a moderate amount of manual energy on the part of the user to control it.

Still another object of this invention is to provide a new and improved control unit connectable to a cloth or fabric pressing machine that will automatically control the operation of the latter so it will do its work effectively without appreciable attention.

A still further object of the herein described invention is to provide a new and improved attachment adapted to control the closing and opening of the head of a fabric pressing machine and automatically enable it to sponge the product involved. Other objects of the present invention will become evident as it is more fully detailed.

In a particular form of the invention, an ancillary mechanism is combined with a standard

2

type of pressing machine with head and buck and comprises a cylinder having a piston therein reciprocating from one end to the other and propelled by fluid pressure from conduits controlled by hand and pedal valves, the pressure being varied by the valves to produce an intermittent reciprocating operating pressing action in the head on the buck, steam being introduced through the head to dampen and sponge the article pressed in similar intermittent manner.

For a better understanding of the invention, and other objects thereof, reference is made to the appended drawings and the following description, that are employed to illustrate the invention by way of example, while the scope of the invention is more particularly outlined in the claims.

In the drawings:

Figure 1 is a side view of a clothes pressing machine embodying this invention,

Figure 2 is a front view of Figure 1 with the valves, levers and piping layed out thereon dia-grammatically,

Figure 3 is a sectional view through the piston,

Figure 4 is a top plane view of Figure 5,

Figure 5 is a sectional view taken along the medial axis of Figure 4,

Figure 6 is an end elevational view of Figure 4, looking in the direction of arrows 6—6 of Figure 4 with the end piece removed, and

Figure 7 is an end elevational view of Figure 4 looking in the direction of arrows 7—7 with the end piece removed, and

Figure 8 is a view partly in section looking in the direction of arrows 8—8 shown in Figure 1.

Similar reference characters refer to similar parts throughout the drawings.

In the structure indicated in the drawings, 10 represents a pressing machine of conventional form having its frame supporting a pressing lever 11 fulcrumed on it by a pin 12. The lever has a pressing head 13 at its operating end which is counterbalanced by a counterweight 14 assembled at the other end. This lever is actuated through a pin 15 fastening it to a toggle-like mechanism.

This toggle mechanism includes an upper arm 16, a lower arm 17 linked together by a pin 18 which forms the toggle apex. The lower arm 17 is hinged on a shaft 19 mounted in the frame of the machine 10. The projecting end 20 connected to the upper arm 16 through the pin 15 has a bifurcated link 21 attached to it and is adjusted by a hand wheel 217 having a screw and nut engagement (not shown) by means of which link 21 is tensioned against a spring 218 having an

abutment on arm 16 and the other abutment on the frame of the machine. A valve 120 and conduit furnish steam to the head 13. The lower arm 17 is arcuately pulled or pushed by a bar 22 and bell crank arm 24 pivoted on a pin 23 on the frame.

A link 25 operated by a lever 26 pivoted on the shaft 19 moves the bar 22 and bell crank 24 when it is given an up and down travel. The portion of the lever 26 extending out beyond the front of the machine 10 is arranged to connect with a link 27 attached to the piston rod 127 of piston 28 in a cylinder 29.

The cylinder is pivotally held to the frame of the machine 10 by a bracket 30. The conduits necessary to supply the cylinder and other parts of the motive fluid system will be referred to in a later portion of the specification. A low pressure pedal valve 31 and a high pressure pedal valve 32 and a manual locking valve 33 and cam operated valve 134 are coupled to this system. The valves 31, and 32, are installed adjacent or on the machine 10 in a location where they can be readily operated by the feet of the operator. The valve 33 is placed on the pressing lever 11 near the head 13 so the operator can reach over easily to operate it when handling the work to be ironed or pressed. The hand valve 33 applies high pressure and tightly applies the head against the buck and holds this position through cooperation of valve 134 until released by pedal 32.

A source of air pressure 34 is used to supply the operative fluid motive power at about 80 pound pressure, which is reduced through a reducing valve 35 to about 35 pounds pressure for the parts utilizing the lower pressure. The conduits 36 carry the high pressure and those marked 37 the lower pressure. All the parts not of the original machine are assembled together as a unit for ease of placement on the machine 10. An equalizing bar 38 is so connected with the pedal valves 31 and 32 that the use of the high pressure valve 32 will also cause the low pressure valve 31 to operate synchronously therewith, but not vice-versa. The construction of the cylinder 29 is indicated in Figure 3. A perforated exhaust manifold 150 with holes 152 allows the exhaust from valves 31 and 32 to escape to the atmosphere when the piston is moving upwardly and downwardly and the valve pedals are released. The high pressure air is conducted to the valve 134 into inlet 161 (or if more convenient into 160) and presses against the ball check 155 on its seat, if the plunger 163 is in the position shown in Figure 5, and is stopped. When the plunger 163 is operated by the cam bar 139 through the mechanism 26, and pulled down, it moves the cam 138 and the plunger 163 follows by opening the valve 134. This opening action raises the ball check 155 off its seat and allows the air pressure to reach the outlet 152 and proceed to the valve 33. The valve 33 has a conventional structure adapted to permit the air under pressure to pass through the inlet conductor and out of the outlet conductor.

The construction of the cylinder member involves the cylinder 29 with the piston 28 reciprocating therein. Its hollow connecting rod 127 passes through a stuffing box in the end of the cylinder and attaches to the lever 26 to operate it on its pivoting shaft 19. An inlet orifice 43 is provided at the top of the cylinder for high and low pressure air, while another inlet 41 is used for high pressure only. When the low pressure is on through the inlet 43 it forces the piston

down towards the bottom of the cylinder but not to the limit of its travel because of the resistance provided to prevent it. Later when the high pressure is introduced through the same inlet 43 and the low pressure is cut off, the high pressure air exerts sufficient pressure to make the piston complete its stroke. The high pressure also tends to escape through the top piston ring and exhaust through the passage 42 in the piston rod. This exhausting action is permitted by providing a hole 40 in the middle of the piston and connecting with the passage 42. If high pressure is introduced through the inlet 41 the piston is returned to its upper position. This action of the piston controls the flow of pressure air so that it incidentally raises the head 13 through the intermediate mechanism as explained further. A check valve 44 is used in the conduits to obstruct low pressure air from passing into the high pressure system.

The lever 26 is provided with a rotatable pin 137 for operating a cam 138 as the lever 26 moves up and down. The cam 138 contacts a roller unit 139 for opening and closing the valve 134. Valve 134 is restored to its original position when not actuated by cam 139 by means of a spring 159.

The valves 31, 32, 33 and 134 are of the same general internal construction shown in Figures 4 and 5 and comprise a center body unit 150 having a longitudinal hole 151 therethrough, and an inlet 152 at right angles to said longitudinal hole although these valves are actuated by elements other than cams as explained further. A grooved push bar 153 is slidably operated in said hole when contacted by balls 154 and 155, which contact seats 156 and 157 respectively. At the rear end a cap 158 is fixed to the body and holds a spring 159 to tension the ball 155. The cap has inlets 160 and 161. At the other end of the body is positioned a fork 162, for supporting the pedals or roller unit 139. A pin 163 is positioned adjacent the fork to move the balls 154 and 155 back and forth through contacting the grooved push bar 153 to open and close the valve. The fork has an exhaust port 164. The fork has a vertically positioned slot 165, and the cap has horizontally positioned slots 166 and 167 to allow for the escape of air around the said balls 154 and 155 when they are moved out of their seats 156 and 157 respectively.

Operation

The operation of the unit is as follows, the machine is assumed to be open with a garment on its buck 130 ready to operate. The user presses the low pressure pedal valve 31. This at first introduces low pressure air into the conduits 37 through valve 31 to push down on the piston and link 27 and move the lever 26 down on its shaft 19. This causes a push on the arm 22 to move the arms 17 and 16 over towards the back of the machine and lower the head 13 with just sufficient force to outbalance the counterweight 14 and rest the head on the garment. The user then opens the locking valve 33 and through cooperation of valve 134 places air pressure of higher value into the cylinder 29 and forces its piston 28 down further by reason of the greater pressure, which actuates the pressing mechanism over more and pushes on the bar 22 sufficiently to make the toggle straighter on the pin 18 and lock same in place, with the head pressure increased by the higher air pressure forcing itself down more strenuously on the garment as shown in Figure 1. At the same time the steam is in-

roduced into the head in a conventional way and tries to escape through the perforations therein through to the garment to dampen same. The steam valve is opened by the manual movement by the user.

The structure of the cylinder 29 and piston 28 will make this action clear. The piston is doubled ringed with a middle escape orifice 40 leading into a passage 42 which passes through the connecting rod to the open air. The purpose of the orifice 40 and passage 42 are to provide an escape for any high pressure air that may pass the rings and attempt to enter the low pressure side of the cylinder. The high pressure pedal 32 is used for two purposes, first; to apply high pressure air to the bottom of the cylinder to unlock the toggle mechanism after it has been set by hand valve 33 the upper cylinder being vented by releasing and venting valve 31. And, secondly; to assist in producing the intermittent motion to the head 13. This intermittent motion is caused in the following manner. The valve 31 is closed and kept closed through the operation. This applies low pressure air to the head of the piston forcing it and the lever 26 and cam downwardly. When the cam 138 contacts the roller 139 it opens the valve 134 and allows high pressure air to pass to valve 32. The valve 32 is then opened by its foot pedal and passes the high pressure air into the cylinder to contact the bottom of the piston forcing it and the head 13 upwardly. As the piston is raised it compresses the low pressure air in the top of the cylinder (which cannot escape because the foot pedal 31 is depressed). The low pressure air is retained to a predetermined extent at the top of the cylinder 29, even though the valve 134 has been opened, due to the fact that the blocking valve 33 has not been manually opened. At a predetermined point the valve 134 is closed by the partial opening of the press, cutting off the high pressure air to valve 32 and venting line 41 through valve 32. The low pressure air then forces the piston and cam downwardly and opens the valve 134 and again sending high pressure air to valve 32 and bottom of the piston and starting the cycle over again. This produces the reciprocating motion to the head known as sponging or the removal of shine from clothing.

While but one general form of the invention is shown in the drawings and described in the specifications, it is not desired to limit this application for patent to this particular form, as it is appreciated that other forms of construction could be made that would use the same principles and come within the scope of the appended claims.

Having thus described the invention, what is claimed is:

1. In combination with a pressing machine of the class described having a frame, a power cylinder mounted on said frame, a piston therein, a control mechanism for controlling the flow of pressure fluid to said cylinder comprising fluid conduits for conveying high and low pressure fluid to said cylinder, a cam bar actuated by said piston, a valve controlling some of said fluid conduits operated by said bar so as to control the high pressure fluid, a manually operated valve mounted on said machine within access of a user thereof, fluid conduit means between said last mentioned valve and said first mentioned valve, a reducing valve, fluid conduit means between one side of said reducing valve and said manually operated valve, fluid conduit means extending from the other side of said reducing valve to one side of said cylinder, a pedal operated valve for controlling fluid flow through said last named conduit means to initiate the closing of said machine fluid conduit means between said first mentioned valve and the opposite side of said cylinder, a second pedal operated valve in the last mentioned fluid conduit means to vary the flow of fluid from said manually operated valve in predetermined amounts, said second pedal operated valves being operable by the user to cause a vibratory action to the fluid flowing to said cylinder and to the pressing elements of the machine operated thereby.
2. A pressing machine as set forth in claim 1, said valve operated by said cam bar comprising a casing, a plurality of ball valves therein, a spacing element between said ball valves, a spring pressing against one of said ball valves and tending to set the device in inoperative position, and a plunger actuatable by said cam bar to force said ball valves in open position.
